(57) **CLAIM**

The ornamental design for a multi tool, as shown and described.

DESCRIPTION

FIG. 1 is a perspective right side and front view of a multi tool;

FIG. 2 is a left side view with the right side view being a mirror image thereof;

FIG. 3 is a rear view thereof;

FIG. 4 is a front view thereof;

FIG. 5 is a top view thereof; and,

FIG. 6 is a bottom view thereof.

The word "MOTA" drawn in dashed lines in FIGS. 1 and 2 forms no part of the claimed design and is drawn to show environmental factors only.
